(57) **CLAIM**

The ornamental design for the swirl taper oil candle, as shown and described.

DESCRIPTION

The present invention relates to the design for the design for a oil candle in the form of a swirl taper.

FIG. 1 is a perspective view of a swirl taper oil candle showing my new design;

FIG. 2 is a front elevational view, the rear and side elevational views being mere images thereof;

FIG. 3 is a top plan view thereof; and,

FIG. 4 is a bottom plan view thereof.

The broken line showing of a candle holder of FIG. 1 is for illustrative purposes only and forms no part of the claimed design.
